UNITED STATES PATENT OFFICE.

NORMAN P. GOODFELLOW, OF CHICAGO, ILLINOIS.

SHEARS-SHARPENING DEVICE.

SPECIFICATION forming part of Letters Patent No. 740,118, dated September 29, 1903.

Application filed April 5, 1902. Serial No. 101,604. (No model.)

To all whom it may concern:

Be it known that I, NORMAN P. GOODFELLOW, a citizen of the United States, and a resident of Chicago, in the county of Cook and State of Illinois, have invented certain new and useful Improvements in Shears-Sharpening Devices, of which the following is a full, clear, and exact description.

The object of my invention is to provide simple, cheap, and effective devices for sharpening shears or scissors which can be easily and satisfactorily operated by any one. This I accomplish by the means hereinafter fully described, and as particularly pointed out in the claims.

In the drawings, Figure 1 is a perspective view of said invention. Fig. 2 is a side view of the same, showing its application to a pair of scissors. Fig. 3 is an edge view of said sharpener. Fig. 4 is a similar view involving a slight modification of the same.

In the drawings, A represents a short section of an ordinary flat file, which may be of any suitable proportions, but which for greater convenience in handling I prefer to make about two inches long and one inch wide and with the teeth arranged thereon at an angle of forty-five degrees.

B represents the gage, which is to be applied to this file for the purpose of enabling the blade of the shears or scissors to be held at a suitable angle to the file, so as to get the proper bevel to its cutting edge when being sharpened. This gage consists of a flat strip of metal of about one inch in width, which is bent so as to form a tube or band that surrounds said file transversely, but has its ends terminate within a short distance of each other. The dimensions of this tubular construction of the gage are such that it presses tightly against the upper and lower surfaces of the file; but I prefer to make the distance between the bends thereof such that the file can have a limited amount of lateral adjustment in the gage. The transverse edge of one end a of the gage is straight, but the other end is extended and bent in an upward inclined direction to form the guard b, against which the blade of the shears or scissors C is held while being sharpened, substantially as shown in Fig. 3 of the drawings.

In operation the flat engaging surface of

the blade of the shears or scissors is placed against the under inclined side of the guard b with its beveled cutting edge resting on the file, and then the file and gage are reciprocated back and forth until the blade is sufficiently sharpened. In order to prevent any lateral movement of the file in the gage, an ordinary wedge D, of wood or other material, may be inserted between the side edge of the file and the bend of the gage, as shown, or, if desired, the relative positions of the gage and file may be determined by the employment of gage-screws d d, as shown in Fig. 4 of the drawings. The object in providing for this lateral adjustability of the file in the gage is to permit of new engaging surface of the file to be presented to the work when the old is worn out, and thus prolong the usefulness of the file. This lateral adjustability of the file can be dispensed with, however, and the dimensions of the gage be made such as to prevent such a possibility.

In order to make the gage clamp the file tightly, I prefer to make it of spring-steel and bow the portion d thereof between the guard b and the return-bend of the gage, with which said guard is connected, so as to make it possible for the gage at the foot of the guard to press the harder against the file.

It is apparent that my invention can be used in conjunction with other shaped files than that described and shown. All such modifications of the shape of the gage as would be required to accommodate the idea to such different shapes I desire to be considered as contemplated within the spirit of my invention.

What I claim as new is—

1. As an article of manufacture, a gage for a shears and scissors sharpener comprising a rectangular band of flat metal the ends of which terminate within a short distance of each other, and one of said ends is extended and bent outward at a suitable angle, and the intermediate portion between said outwardly-bent portion and the return-bend of the band with which it is directly connected is bowed outward.

2. As an article of manufacture, a shears and scissors sharpener comprising a flat file, and a gage consisting of a suitable band of such dimensions that it clamps the broad surfaces

of the file but permits the lateral adjustment thereof, having its ends terminate within a short distance of each other and one of said ends bent outward to form a guard; and 5 means for locking said file in its laterally-adjusted position.

3. As an article of manufacture, a shears and scissors sharpener, comprising a flat file, a gage consisting of a suitable band of such dimensions that it tightly clamps the broad surfaces of the file but permits the lateral ad-

justment of the same within it, and has its ends terminate within a short distance of each other, and one of said ends being bent outward to form a guard, and a wedge for locking said file in its laterally-adjusted position within the same. 15

NORMAN P. GOODFELLOW.
